ROTARY PUMP

Robert Deming, Norwood, Ohio, assignor to Deming Rotary Pump Company, Cincinnati, Ohio, a corporation of Ohio

Application December 11, 1934, Serial No. 756,989

12 Claims. (Cl. 103—136)

This invention relates to fluid pressure or vacuum pumps of the rotary piston type and has for its object to provide a pump in which the leakage of the fluid being pumped past relatively moving parts of the pump is reduced to a minimum, and in which the pressure in the high pressure side of the pump chamber is utilized to maintain a fluid-tight engagement between the vanes which act as pistons or sealing members and the relatively movable parts with which they engage, so as to reduce leakage past such pistons or sealing members from the high pressure side to the low pressure side of the pump chamber.

A further object of the invention is to provide a pump in which the relatively movable parts are provided with sealing grooves so disposed as to effectively check flow of the fluid being pumped between the relatively movable contacting surfaces of the pump elements.

20 A further object is to so conduct, apply and utilize the normal forces generated by the pumping operation as to make the sealing provisions more effective.

With the above and other objects in view, the invention may be said to comprise the pump as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification, in which:

35 Figure 1 is a transverse section through a rotary pump embodying the invention, a section being taken at right angles to the axis of the pump and through the body of the rotor;

40 Fig. 2 is a perspective view of the body portion of a pump vane;

Fig. 3 is a perspective view of a sealing shoe with a convex working face for engagement internally with a cylindrical surface;

45 Fig. 4 is a perspective view of a sealing shoe with a concave working face for engagement externally with a cylindrical surface;

Fig. 5 is a diagrammatic view showing the pressures exerted upon the shoes;

50 Fig. 6 is a diagrammatic view showing the pressures exerted upon the vane;

Fig. 7 is a sectional view showing a pump with a one-piece vane;

Fig. 8 is a perspective view of the one-piece vane shown in Fig. 7;

55 Fig. 9 is a diagrammatic view showing the effect

of centrifugal force on a vane disposed at an angle to the radius;

Fig. 10 is a view similar to Fig. 9 showing the vane oppositely inclined; and

Fig. 11 is a sectional view showing a multivane 5 pump embodying the invention.

An important feature of the present invention is the provision of an effective seal between relatively sliding parts of a rotary pump such as a sliding vane or an oscillatable shoe, and the parts 10 with which the vane or shoe has sliding contact.

In the following description, it is to be understood that by "working face" of a vane or shoe, is meant that face of the vane or shoe which engages with a part of the pump which is relatively rotatable with respect to the part which carries the vane or shoe.

The faces of the shoe or vane perpendicular to the axis of rotation, are referred to as "end faces".

20 The faces of the vane or shoe opposite the working face, are referred to as "bottom faces".

The side of the shoe or vane disposed transversely to the direction of rotation and which receives the initial pressure from the fluid being pumped, is referred to as "the high pressure side 25 or face", and the corresponding side of the recess in which the shoe or vane is mounted is referred to as "the high pressure side or face". The face of a shoe or recess opposite the high pressure side 30 or face is referred to as "the low pressure face or side". Grooves, channels, recesses, or spaces provided for the purpose of applying and directing pressure forces are sometimes referred to herein as "pressure pockets".

35 In Figure 1 of the drawings, there is shown a pump housing 1 enclosing a cylindrical chamber in which there is mounted a rotor 2, the axis 3 of which is disposed eccentrically with respect to the cylindrical housing, the rotor 2 being of cylindrical form and of smaller diameter than the chamber in which it is mounted. The rotor is positioned with its periphery in contact with the chamber wall along a longitudinal tangent line to provide a seal between the inlet and outlet ports. The rotor 2 has a longitudinal slot 4 in which is slidably mounted the body portion 5 of a sealing vane, the working face of which is provided with an oscillatable shoe 6 having an arcuate convex bottom or seating face 7 which fits 45 in an arcuate recess in the body portion 5.

The shoe 6 has a convex working face 8, the radius of which corresponds to that of the cylindrical chamber, and which contacts with the wall of the cylindrical chamber. The bottom 50 55

or seating face 7 of the shoe 6 is of shorter radius than the working face 8 and intersects the working face at opposite sides of the shoe.

During operation of the pump the vane consisting of the slidable body portion 5 and oscillatable shoe 6 is pressed outwardly towards the cylindrical wall of the pump chamber, to maintain the working face 8 of the shoe in contact throughout its width and length with the cylindrical wall of the chamber. The vane provides a partition moving with the rotor to force fluid from the inlet to the outlet of the pump.

In order to provide a more effective seal between the rotor and the chamber wall along the line of contact between the rotor and wall, an oscillatable shoe 9 is mounted in a recess in the housing and this shoe has an arcuate convex bottom or seating face 10 which fits in an arcuate recess in the housing wall, and an arcuate concave working face 11 of the same radius as the rotor which bears against the surface of the rotor. The bottom or seating face 10 is a shorter radius than the working face 11 and intersects the working face at opposite sides of the shoe. The shoe 9 maintains contact with the rotor to provide a more effective seal between the inlet and outlet.

As shown in Fig. 2 of the drawings, the body portion 5 of the vane has parallel longitudinal grooves 12 on its low pressure face and longitudinal channels 14 on the high pressure face thereof. On the high pressure side there is at least one passage 15 which opens at one end to the shoe seating recess and at its opposite end to the bottom of the vane. The passage 15 is intersected by the channels 14 which provide pressure pockets along the high pressure face of the vane for fluid under pressure which acts to press the vane toward the low pressure wall of its recess or slot so that the sealing grooves 12 are effective to prevent leakage of fluid from the bottom of the recess through the space between the low pressure wall of the vane and the adjacent wall of the recess. The ends of the body portion 5 of the vane are provided with diagonal grooves or channels 16 which serve to retard leakage past the ends of the vane. The diagonal channels 16 also receive fluid under pressure which exerts a force on the vane toward the low pressure wall. The grooves or channels 16 aid in scavenging to the high pressure side the space between the bottom of the vane and the bottom of the slot 4 when the vane is retreating into the slot.

As shown in Fig. 3 of the drawings, the shoe 6 has longitudinal channels 17 on the high pressure side of its working face 8 and longitudinal channels 18 on the high pressure side of its seating face 7. The channels 17 and 18 are intersected by at least one channel 19 intermediate the ends of the shoe and disposed at right angles to the channels 17 and 18. The channel 19 is open to the high pressure side of the vane and registers with the passage 15 of the body portion 5 of the vane to deliver fluid under pressure to the channels 14 and to the bottom of the slot 4. The grooves or channels 17 and 18 provide pressure pockets on the high pressure side of the shoe, and the channel 19, which opens to the interior of the pump chamber on the pressure side of the vane supplies fluid under pressure to these grooves or channels as well as to the passage 15 which conducts fluid under pressure to the channel 14 on the high pressure face of the body portion of the vane and to the bottom of

the slot 4. The shoe 6 also has longitudinal sealing grooves 20 on the low pressure side of the working face 8 and similar grooves 21 on the low pressure side of the bottom or seating face 7. One or both end faces of the shoe 6 may be provided with transverse sealing grooves 22 to impede the flow between the end face of the shoe and the end walls of the pump chamber.

Referring to Fig. 4 of the drawings, the shoe 9 has longitudinal channels 24 forming pressure pockets on the high pressure side of its working face 11 and longitudinal channels 25 forming pressure pockets on the seating face 10 thereof. Channels 24 and 25 are intersected by at least one channel 26 intermediate the ends of the shoe which extends substantially at right angles to the grooves or channels 24 and 25. The channel 26 opens to the high pressure side of the shoe 9, and conducts fluid under pressure to the pressure pockets formed by the channels 24 and 25. The shoe 9 has longitudinal sealing grooves 27 on the low pressure side of its working face and similar sealing grooves 28 on the low pressure side of its seating face 10.

During operation of the pump fluid under pressure will be admitted through the channel 19 to the pressure pocket channels 17 and 18 of the shoe 6 and through the channel 26 into the pressure pocket channels 24 and 25 of the shoe 9, and the fluid under pressure in these pockets will exert a thrust on the shoes 6 and 9, pressing them toward the low pressure sides of their recesses. The conductor channels 19 and 26 provide direct passages for fluid to the pressure pockets on the high pressure sides of the shoes so that the fluid in the pockets is subjected to the pressure of the fluid being pumped at each instant of the pumping cycle.

In Fig. 5 of the drawings, the arrows 29 and 30 indicate the forces applied by the fluid under pressure to the shoes 6 and 9. The force of the fluid under pressure indicated by the arrows 29 is outwardly of the center of curvature 31 of the bottom or seating face 7 of the shoe 6 and tends to rotate the shoe in a direction to move the leading edge of the shoe inwardly, opposing the frictional drag exerted on the working face 8. Similarly the fluid pressure on the shoe 9, indicated by the arrows 30, is outwardly of the center of curvature 32 of the bottom or seating face 10 and tends to rotate the shoe in a direction to move the high pressure side thereof into the shoe recess. These forces are transmitted to the faces of the shoes in which the sealing grooves are located, as indicated by the arrows 37, 38, 39 and 40, the pressure on the shoes being commensurate with the pressure under which the vane is working. It should be noted that the low pressure side of the sealing shoe 6 is wedge-shaped so that the shoe is pressed against the wall of the housing, as indicated by the arrows 38, and against the recess wall, as indicated by the arrows 37, so that the sealing grooves in these spaces can effectively impede the leakage of fluid past the shoe. Similarly, the low pressure side of the shoe 9 is wedge-shaped, so that the surfaces in which the sealing grooves are located are pressed against the rotor and the recess wall, as indicated by the arrows 39 and 40.

It will be observed that the high pressure side of the recess in which the shoe 9 is mounted, opens to the pump chamber at or near the line where the rotor 2 contacts with the wall of the housing, so that as the shoe 6 comes into contact with the shoe 9 the working faces of both sub-

stantially coincide with the contact line and since the fluid pressure acting on the two shoes tends to move the high pressure side of the shoe 6 inwardly and the high pressure side of the shoe 9 outwardly, a clearance is provided between the opposed sharp edges of the shoes and there is no interference to the passage in the shoe 6 past the shoe 9.

Figure 6 of the drawings illustrates diagrammatically the forces acting upon a vane. The arrow 42 represents the direction and amount of pressure due to the film of fluid between the face of the rotor chamber and the face of the vane. The arrow 43 represents the force due to the working pressure against the bottom of the vane of the fluid admitted to the bottom of the slot 4. The forces 42 and 43 are normally equal and opposed and are equalized. The arrow 44 represents the force of a spring commensurate with operating conditions, such a spring being used where the speed of rotation and delivery pressure and physical properties of fluid being pumped are such that a force in addition to the centrifugal force and that of fluid pressure is desirable. The arrow 45 represents the added force encountered when the vane is receding into its slot and scavenging the chamber at the bottom of the slot. This force is a valuable factor as it adds to the pressure making the seal at the working face of the vane during a portion of rotation in which the fluid is being compressed or delivered.

It will be noted that the vane of the present invention adds to the efficiency and capacity of the pump, since it acts as a piston pump, causing the fluid which has filled the chamber at the bottom of the slot 4 during the outward movement of the vane to be discharged against a higher pressure at the delivery side of the vane during the retreating movement of the vane.

The arrow 46 represents a force due to friction. The arrow 47 represents a force at the point of application due to the pressure of the load. The arrow 48 represents the resultant of 46 and 47 at its point of application.

In the usual vane pump the force 48 is opposed by a force, indicated by the arrow 49, at a fulcrum point formed by the edge of the slot 4 on the low pressure side thereof. A force, indicated by the arrow 50, is also exerted against the bottom corner of the vane on the high pressure side thereof. The forces 48 and 50 balanced against the fulcrum point 49 tend to cant the vane in its slot, creating localized pressures at the points of application of the forces 49 and 50, which are the cause of rapid wear of the vane and slot and quick deterioration in efficiency of operation.

The present invention provides means for more advantageously distributing the forces acting on the vane so as to increase the efficiency and reduce wear on the sliding parts. The arrow 51 represents the force exerted on the vane by the fluid under pressure in the pressure pocket channels 14. The pressure, indicated by the arrow 51, is more than sufficient to eliminate the pressure 50 of the bottom corner of the vane against the high pressure wall, and distributes the pressure of the vane over the low pressure wall of the slot so as to eliminate the fulcruming pressure indicated by the arrow 49. The wear is thus distributed over the surfaces of the vane and slot walls and the force balancing the pressures 51 and 48 may be represented by the arrow 52 a substantial distance inwardly of the point about which the vane would normally fulcrum.

The arrow 53 represents the resultant of forces indicated by the arrows 42, 43, 44 and 45 acting longitudinally of the vane. The center of weight of the vane is indicated at 54 and the arrow 55 represents the centrifugal force derived therefrom, and this force is also exerted radially. Variations in dimensions and speed of rotation alter the force 55.

The principle of the present invention is applicable to pumps operating at high speed or 10 at low speed, and for pumping gases or liquids. Obviously, the forces 42, 43, 44 and 45 may be controlled to meet the requirement of the individual pump to provide, in conjunction with the centrifugal force, the radial pressure desired. 15

In Figs. 7 and 8 of the drawings, there is here shown a rotary pump employing a one-piece vane. This pump has a housing 70 and a rotor 71 within the housing which carries a sliding vane 72 mounted in a slot 73 in the rotor. The 20 vane 72 has a convex working face 74 which is provided with longitudinal sealing grooves 76 on the low pressure face thereof and with pressure pocket channels 77 extending longitudinally of the high pressure face near the bottom 25 thereof. A passage 78 adjacent the high pressure face of the vane extends from the working face 74 to the bottom of the vane and intersects each of the channels 77. The upper end of the passage 78 has a lateral opening 79 to the high 30 pressure face of the vane so that fluid under pressure passes through the passage 78 to each of the pressure pocket channels 77 and to the space at the bottom of the slot between the bottom of the slot and the bottom face of the vane, 35 so that, during operation of the pump, lateral pressure is applied to the high pressure face of the vane near the bottom edge thereof, and radial pressure is also applied to the bottom face of the vane to force the same outwardly against 40 the wall of the pump chamber. Diagonal grooves 80 are provided on the ends of the vane to impede leakage of fluid past the ends of the vane between the ends of the vane and the end walls of the pump chamber, the grooves 80 also serving to apply an additional lateral thrust to the vane and to facilitate the escape of fluid from the bottom of the slot during the receding movement of the vane to the high pressure side. 45

In some pumps it may be desirable to modify 50 the action of centrifugal force upon the vane by disposing the slots, in which the vanes slide, at an angle to the radius. If it is desired to reduce the high frictional resistance due to the load or speed of rotation, or both, the vane may be placed 55 as shown diagrammatically in Fig. 9, with its working face advanced relative to the direction of rotation. The force 85 representing the thrust of the fluid being pumped in a direction perpendicular to a radius is shown resolved into its 60 components 86 and 87, component 86 being perpendicular to the vane, and component 87 acting inwardly in a direction of movement of the vane. The centrifugal force 55 at the center of weight 54 is shown resolved into its components 88 and 89, component 88 acting perpendicular to the vane, and component 89 acting outwardly. 65

The components 87 and 89 act in the same line but in opposite directions. They must be 70 subtracted, and the resultant outward force which causes frictional resistance is reduced, as desired, by the degree of the angle at which the vane is placed. Also, it is obvious that a resultant of forces 86 and 88 may be found per- 75

pendicular to the radius and that it will be less than the corresponding resultant on the radial vane illustrated in Fig. 6. Since this force perpendicular to the radius is a measure of the torque, it is apparent that less power will be required to operate a pump having its vane or vanes inclined as shown in Fig. 9.

The force 88 is added to the force 81 which holds the vane against the low pressure wall of its recess surface to surface, due to the fact that the center of weight is transferred from a position on the high pressure side to a position on the low pressure side of a radial line passing through the fulcrum 49.

In Fig. 10 of the drawings the angularity of the vane is the reverse of that shown in Fig. 9, the thrust of the fluid being pumped which is indicated by the arrow 85^a being resolved into components 86^a and 87^a and the centrifugal force at the center of weight indicated by the arrow 55 being resolved into components 88^a and 89^a. In this case the components 87^a and 89^a in the direction of movement of the vane are not opposed as in Fig. 9 but act in the same direction and their resultant is their sum instead of their difference.

It is to be understood that the pressure pockets at the high pressure sides of the vane and shoe and the passages for conducting fluid from the pump chamber to such pockets may be formed in various ways, it being essential only that such pockets and passages be so disposed as to cause the fluid to exert an effective pressure against the grooved sealing faces.

In Fig. 11 of the drawings there is shown a multi-vane pump having a casing 92 with a cylindrical chamber 93, a rotor 94 disposed eccentrically of the chamber and having a series of vanes 95 which are mounted in slots 96 in the rotor which are disposed at an angle to radii of the rotor. The casing and vane are provided with shoes 97 and 98 which may be of the same construction as the shoes 6 and 9 previously described. The shoe 98 may be wider than the vane in which case the rotor has recesses 99 at the high pressure sides of its slots to accommodate the shoes. The vanes 95 have their inner ends tapered, providing an inclined face 100 which is subjected to fluid pressure which acts to press the vane against the low pressure wall of its slot. The inclined face 100 provides a pressure pocket on the high pressure side of the vane which is in communication at all times with the bottom of the slot to which fluid under pressure is conducted by channels or passages as in the modifications previously described.

It will be apparent that the present invention provides a simple construction in which the various forces acting on the vanes and shoes are advantageously distributed to lessen sliding friction and wear on the parts and to provide an effective seal.

Furthermore, it is to be understood that the particular form of apparatus shown and described, and the particular procedure set forth, are presented for purposes of explanation and illustration and that various modifications of said apparatus and procedure can be made without departing from my invention as defined in 70 the appended claims.

What I claim is:

1. In a pump of the rotary piston type having relatively rotatable elements forming walls of the pump chamber, and a movable sealing member 75 having a sliding fit in a recess of one of said ele-

ments and provided with a face engaging the surface of a relatively rotatable element and substantially conforming to said surface to maintain a seal between high pressure and low pressure portions of the pump chamber, said sealing member and said recess in which it is mounted being shaped to provide spaced pressure pockets between the member and its recess at the high pressure and under sides of said member, said sealing member and its recess having bearing surfaces 10 extending the full length of said member and in sliding and sealing engagement on the low pressure side thereof, said sealing member having a passage for fluid under pressure opening at one end to the pump chamber on the high pressure 15 side of said member and communicating with said pockets to maintain a fluid pressure therein substantially the same as in the high pressure portion of the pump chamber to press said member against the relatively rotatable element and 20 against the low pressure side of its recess.

2. In a pump of the rotary piston type having relatively rotatable elements forming walls of the pump chamber, and a movable sealing member having a sliding fit in a recess of one of said elements and provided with a face engaging the surface of a relatively rotatable element and substantially conforming to said surface to maintain a seal between high pressure and low pressure portions of the pump chamber, said member having parallel sealing grooves extending throughout its length in the face thereof which engages the relatively rotatable element and also in the face thereof which engages the wall of the recess on the low pressure side, said sealing member and said recess in which it is mounted being shaped to provide spaced pressure pockets between the member and its recess at the high pressure and under sides of said member, said sealing member and its recess having bearing surfaces 35 extending the full length of said member and in sliding and sealing engagement on the low pressure side thereof, said sealing member having a passage for fluid under pressure opening at one end to the pump chamber on the high pressure 40 side of said member and communicating with said pockets to maintain a fluid pressure therein substantially the same as in the high pressure portion of the pump chamber to press said member against the relatively rotatable element and 45 against the low pressure side of its recess.

3. A pump of the rotary piston type having relatively rotatable elements forming walls of the pump chamber, a member slidably mounted in a recess of one element and engaging the surface 55 of a relatively rotatable element and substantially conforming to said surface to maintain a seal between high pressure and low pressure portions of the pump chamber, said member having sealing grooves in the faces thereof which engage 60 the relatively rotatable element and the wall of the recess on the low pressure side, said member having longitudinal channels in the face thereof which engages the recess wall on the high pressure side and a passage communicating with said 65 channels and opening to the pump chamber on the high pressure side of said member.

4. A pump of the rotary piston type having relatively rotatable elements forming walls of a pump chamber, one of said elements having a 70 slot, a vane in said slot for maintaining a seal between high pressure and low pressure portions of the pump chamber, said vane comprising a body portion slidable in said slot and having an arcuate recess and a shoe having an arcuate face 75

seating in said recess whereby the shoe is adapted to rock laterally in said arcuate recess, said shoe being interposed between the said body portion and a relatively rotatable element, means for applying fluid pressure to the bottom and low pressure side of the body portion of the vane, and means including passages formed between the arcuate face of the shoe and the arcuate recess in the vane for applying fluid pressure to the bottom of said shoe, and sealing grooves for impeding the flow of fluid past said vane between the shoe and relatively rotatable member, between the shoe and the low pressure side of its recess and between the body portion of the vane and the low pressure side of the slot.

5. A pump of the rotary piston type having relatively rotatable elements forming walls of a pump chamber, one of said elements having a slot, a vane in said slot for maintaining a seal between high pressure and low pressure portions of the pump chamber, said vane comprising a body portion slidable in said slot and having an arcuate recess and a shoe mounted to rock laterally in said arcuate recess and interposed between the said body portion and a relatively rotatable element, the body portion of the vane having a passage extending from the arcuate recess to the bottom of the vane, the shoe having an arcuate bottom seated in said recess, means forming a transverse passage extending partially across the bottom of the shoe from the high pressure side thereof and registering with the passage in the body portion of the vane to maintain communication between the bottom of the slot and the portion of the pump chamber immediately in front of the vane, grooves longitudinal with respect to the vane impeding flow of fluid between the vane and low pressure side of its slot and between the low pressure sides of the seating and working faces of the shoe and surfaces engaged thereby, pressure pockets on the seating and working faces of the shoe at the high pressure side which communicate with said transverse passage, and a pressure pocket on the high pressure side of the body portion of the vane which communicates with the passage in the body portion of the vane.

6. A pump of the rotary piston type having relatively rotatable elements forming walls of a pump chamber, one of said elements having a slot opening to the space between said elements, a vane slidably fitting in said slot and having a working face slidably engaging the other of said elements to maintain a seal between high pressure and low pressure portions of the pump chamber, said vane having a plurality of parallel sealing grooves on its working face, a plurality of parallel sealing grooves on its low pressure side inwardly of the open end of the slot and a recess forming a pressure pocket on the high pressure side of the vane inwardly of the open end of the slot, and a passage in said vane opening to the high pressure side thereof adjacent the working face, said passage extending to the bottom of the vane and communicating with said pressure pocket.

7. A pump of the rotary piston type having relatively rotatable elements forming walls of a pump chamber, one of said elements having a slot, a vane in said slot for maintaining a seal between high pressure and low pressure portions of the pump chamber, said vane having sealing grooves on its working face and its low pressure side, diagonal grooves on its end faces, pressure

pockets on its high pressure side, and a passage communicating with said pockets and opening to the high pressure side of the vane adjacent its working face.

8. In a pump of the character described, relatively rotatable elements forming walls of a pump chamber, one of said elements having an arcuate surface, the other of said elements having an arcuate recess with a radius of curvature less than that of said surface, a sealing shoe having an arcuate seating face fitting in said recess and an arcuate working face which conforms to said arcuate surface to provide a seal between high and low pressure portions of the pump chamber, each of said arcuate faces of the shoe having a transverse channel extending from the high pressure side thereof partially across said face, and longitudinal grooves in said faces intersecting said channels and forming pressure pockets on the working and seating faces of the shoe adjacent the high pressure side thereof.

9. In a pump of the character described, relatively rotatable elements forming walls of a pump chamber, one of said elements having an arcuate surface, the other of said elements having an arcuate recess with a radius of curvature less than that of said surface, a sealing shoe having an arcuate seating face fitting in said recess and an arcuate working face which conforms to said arcuate surface to provide a seal between high and low pressure portions of the pump chamber, each of said arcuate faces of the shoe having a transverse channel extending from the high pressure side thereof partially across said face, longitudinal grooves in said faces intersecting said channels and forming pressure pockets on the working and seating faces of the shoe adjacent the high pressure side thereof, and additional longitudinal sealing grooves in the working and seating faces of said shoe between the low pressure side of the shoe and the inner ends of said channels.

10. A rotary piston pump having relatively rotatable, eccentrically disposed elements, one forming the cylindrical outer wall of the pump chamber and the other being of smaller diameter and forming the cylindrical inner wall of the chamber and tangentially disposed with respect to the outer wall, a vane carried by one element and comprising a slidably mounted body portion provided with an arcuate recess and a shoe having an arcuate face of a curvature corresponding to that of the recess and seating in said recess and an arcuate working face of the same curvature as the relatively rotatable element, an arcuate recess in the other element and an arcuate shoe in said recess having a seating face conforming to said recess and a working face conforming to the surface of the rotating element, the arcuate seating face of said last named shoe being slidably in the arcuate recess in a direction transversely of the axis of the seating face and adapted to turn about the axis of its seating face, and means for applying fluid pressure to arcuate faces of said shoes in directions tending to rotate each shoe on its seat in a direction to relieve the pressure on the working face adjacent the high pressure side of the shoe whereby the opposed edges of the shoes are retracted as the shoe on the rotating element approaches the shoe on the stationary element.

11. A rotary piston pump having relatively rotatable, eccentrically disposed elements, one forming the cylindrical outer wall of the pump chamber and the other being of smaller diameter

and forming the cylindrical inner wall of the chamber and tangentially disposed with respect to the outer wall, a vane carried by one element and comprising a slidably mounted body portion 5 provided with an arcuate recess and a shoe having an arcuate face of a curvature corresponding to that of the recess and seating in said recess and an arcuate working face of the same curvature as the relatively rotatable element, an 10 arcuate recess in the other element and an arcuate shoe in said recess having a seating face conforming to said recess and a working face conforming to the surface of the rotating element, each shoe having pressure pockets adjacent its 15 high pressure edge adapted to receive fluid under pressure which tends to rotate the shoe about the center of curvature of its seating face.

12. A rotary piston pump having relatively rotatable, eccentrically disposed elements, one

5 forming the cylindrical outer wall of the pump chamber and the other being of smaller diameter and forming the cylindrical inner wall of the chamber and tangentially disposed with respect to the outer wall, one of said elements having a slot, a vane slidably mounted in the slot and engaging the relatively rotatable element, said vane having a passage opening at one end at the high pressure side of the vane to the pump chamber and at the other end to the bottom of said slot 10 whereby said vane acts as a piston pump during relative rotation of said elements, said vane having grooves on its end faces which extend diagonally from the bottom to the high pressure side of the vane to impede flow toward the low pressure side and to conduct fluid to the high pressure side of the vane. 15

ROBERT DEMING.
